ABSTRACT OF THE DISCLOSURE

Optical brightener compounds defined as 2-benzisothiazolyl - S - dioxide compounds, *o*-disulfophenylimidinyl compounds and benzisothiazolyl-S-dioxide compounds. The optical activity of these compounds can be employed to advantage in the optical brightening of a wide variety of natural and synthetic materials. They are useful in the brightening of fabrics and find application in the preparation of laundry detergent compositions and hypochlorite bleach-containing compositions.

BACKGROUND OF THE INVENTION

This is a division of application Ser. No. 846,601, filed July 31, 1969, now issued as U.S. Pat. No. 3,711,474, patented Jan. 16, 1973.

This invention relates to optical brightening agents. More particularly, it relates to optical brightening agents useful in the optical brightening of a wide variety of materials and to detergent and hypochlorite bleach-containing compositions containing them.

In recent years, the use of optical brightening agents, oftentimes termed optical bleaches or fluorescers, has grown enormously. These compositions which are colorless dyestuffs function by absorbing light in the ultraviolet range (300-400 nm.) such as is contained in natural daylight and remitting this as visible, blue-white light (400-500 nm.). This fluorescence masks natural yellowing of textile fibers and results in a highly desirable blue-white "glow" on white goods and a fresher, cleaner appearance of colored goods. The fluorescence of optical brightening agents, while in the blue range, varies somewhat in dominant wavelength. Where the dominant wavelength is longer, the blue fluorescence is considered to have a slightly greenish tinge. A shorter dominant wavelength near the violet end of the spectrum results in blue fluorescence which is slightly reddish. For practical purposes, particularly for use in laundry detergent formulations, a neutral blue fluorescence is generally preferable.

Optical brighteners suitable for textile applications must exhibit a high degree of fluorescence. Frequently, the fluorescence of conventional optical brighteners is destroyed or quenched by contact with hypochlorite and similar oxidizing bleaches. Since many of the deeply embedded soils and stains encountered in the laundering of textile fabrics are conventionally removed by the action of chemical bleaching, great effort has been expended in the search for optical brighteners which resist the destructive effects of hypochlorite bleaches.

Accordingly, it is an object of this invention to provide novel optical brighteners having a high degree of fluorescence and resistance to the destructive effects of hypochlorite bleaches.

Another object of this invention is to provide detergent compositions containing an organic detergent, an alkaline builder salt and an optical brightener.

2

A further object of this invention is to provide laundry detergent compositions containing an organic detergent, an alkaline builder salt, a bleaching compound and an optical brightener.

Still another object of this invention is to provide aqueous hypochlorite and granular bleach compositions containing an optical brightener.

Other objects of this invention will become apparent from consideration of the detailed description of the invention which appears hereinafter.

SUMMARY OF THE INVENTION

The above and other objects of this invention are achieved by the present invention which comprises the provision of optical brightener compounds of the formula:

wherein each *a* is an integer from 1 to 4; *x* is 0 or 1;

25 each *A* is selected from hydrogen; alkyl of 1 to 10 carbon atoms (e.g., methyl, ethyl, propyl, butyl, octyl, decyl), preferably of 1 to 4 carbon atoms; halogen (e.g., chlorine, bromine); alkoxy of 1 to 10 carbon atoms (e.g., methoxy, butoxy, hexyloxy, decyloxy); aryl of from 6 to 12 carbon atoms (e.g., phenyl, biphenyl, naphthyl); alkylsulfonyl of from 1 to 10 carbon atoms (e.g., methylsulfonyl, octylsulfonyl, decylsulfonyl); alkoxyalkyl of from 2 to 10 carbon atoms (e.g., methoxymethyl, butoxymethyl, ethylhexyloxyethyl); polyethylenoxy of the formula $H(CH_2CH_2O)_n$ where *n* is an integer from 1 to 10 (e.g., $CH_3CH_2CH_2O$); haloalkyl of from 1 to 10 carbon atoms (e.g., trifluoromethyl, perfluoroethyl, chloroethyl); alkanoyl of from 2 to 10 carbon atoms (e.g., acetyl, propionyl, hexanoyl, octanoyl, decanoyl);

30 cyano; polyhydroxyalkyl of from 1 to 10 carbon atoms (e.g., 1,2,3-trihydroxypropyl, sorbitol); *X* is selected from $\begin{array}{c} \text{O} \\ \text{S}=\text{O} \\ \text{---S---} \\ \text{---CH}_2\text{---} \\ \text{---O---} \end{array}$; 35 when *x* is zero, *Z* is a monovalent radical selected from (1)

40 50 wherein each *b* is an integer from 1 to 4 and each *B* is defined as *A* above; $-\text{SO}_2\text{OM}$ where *M* is hydrogen or alkali metal; or

wherein *R* and *R'* are each hydrogen, alkyl of 1 to 4 carbon atoms, hydroxyalkyl of from 1 to 4 carbon atoms, aryl, glucosyl or together comprise a ring structure; and

60 65 wherein each *A* is as hereinbefore defined and each *p* is 1 or 2; and when *x* is one, *Y* and *W* are each selected from

and Z is a bivalent radical of the formula

wherein each B and each b are as defined hereinbefore. 10

The compounds prepared according to the present invention are excellent optical brighteners for use in a variety of natural and synthetic materials and are especially characterized by their resistance to the destructive action of chlorine-containing bleaching compounds. Accordingly, they can be employed in detergent compositions containing alkaline builder compounds and active chlorine-containing bleaching compounds and in aqueous and granular bleach compositions.

DETAILED DESCRIPTION OF THE INVENTION

The optical brightener derivatives of the present invention having the hereinbefore defined formula are characterized herein as 2-benzisothiazolonyl-S-dioxide compounds, α -disulfophenylimidinyl compounds and benzisothiazolyl-S-dioxide compounds when they are characterized by the presence of

groups, respectively, wherein A and n are as defined hereinbefore.

The optical brighteners of the present invention are derived from fluorescent aromatic primary mono- or diamines characterized by ultraviolet absorption in the 310 to 400 nanometer range and fluorescence in the 400 to 475 range. These fluorescent amines can be represented by the formula $(H_2N)_q-Z$, wherein Z represents the residue of the fluorescent amine, i.e., the entire molecule exclusive of the amino group and q is one in the case of a mono-amine and two in the case of a diamine. The equimolar condensation reaction of a monoamine with a reactive aromatic dihalide to form a 2-benzisothiazolonyl-S-dioxide, *o*-disulophenylimidinyl or benzisothiazolyl-S-dioxide compound is illustrated by the following reaction scheme:

wherein X is

and Z is the residue of a fluorescent aromatic amine as hereinbefore defined.

Similarly, fluorescent aromatic diamines having the same spectral characteristics and represented as

undergo reaction with a reactive aromatic halide according to the following scheme:

Compounds having a 2-benzisothiazolonyl-S-dioxide, *o*-disulfophenylimidinyl or benzisothiazolyl-S-dioxide group and an additional cyclic moiety of different configuration correspond to the formula

wherein X, Z, Y and W are hereinbefore defined and Y and W are such as to comprise a cyclic structure different from that containing group X. The compounds can be conveniently prepared by reacting one mole of an aromatic diamine with one mole of reactive aromatic halide to form an intermediate which is thereafter reacted with one mole of a different aromatic halide to produce the desired compound.

35 This reaction can be illustrated by the following reaction scheme:

60 The intermediate compound can also be prepared by other convenient methods. For example, a phthalimidinyl compound.

70 can be prepared by equimolar reaction of disodium 4,4'-diamino-2,2'-stilbenedisulfonate with phthalide. Reaction of the resulting compound, disodium 4-phthalimidinyl-4'-amino-2,2'-stilbenedisulfonate, with an equimolar amount of α -chloro- α -toluenesulfonyl chloride, results in the formation of an optical brightener having excellent fluores-

ence, Bleach compatibility and substantivity corresponding to the formula

disodium 4-(1-phthalimidinyl)-4'-(2-benzisothiazolyl-S-dioxide)-2,2'-stilbenedisulfonate

The radical Z, where employed herein is used to represent the radical derived by abstraction of one or two primary amino groups from a fluorescent aromatic amine described hereinbefore. It will be understood that this radical is considered as being derived by abstraction for convenience only and that the characterization of the amine residue in such terms is not intended to imply that abstraction in a chemical sense is actually involved in the formation of the brightener compounds of the present invention.

The amines which can be employed to prepare the optical brighteners of the present invention are fluorescent aromatic primary mono- and diamines characterized by ultraviolet absorption in the range of 310 to 400 nm. and fluorescence in the 400-475 nm. range. These compounds are conventional brightener chromophores known to those skilled in the art. Examples of fluorescent amines having the prescribed spectral characteristics and their monovalent or bivalent radicals (Z) include the following:

(1) 4-aminostilbenes of the formula:

where each b is as defined above and each B is defined as A above or

where M is hydrogen or an alkali metal (e.g., sodium, potassium, lithium); and R and R' are each hydrogen or alkyl of 1 to 4 carbon atoms, (e.g., methyl, ethyl, n-propyl, isopropyl, sec-butyl); aryl (e.g., phenyl); glucosyl; hydroxyalkyl of 1 to 4 carbon atoms (e.g., 2-hydroxyethyl) or R and R' together comprise a ring structure (e.g., pyridyl, morpholino);

(2) 4,4'-diaminostilbenes of the formula:

where each b is as defined above and each B is defined the same as A above or

where M is hydrogen or an alkali metal; and R and R' are each hydrogen; alkyl of 1 to 4 carbon atoms; aryl; 75

glycosyl; hydroxyalkyl of 1 to 4 carbon atoms or together comprise part of a ring structure; and

(3) 7-aminocoumarins of the formula:

wherein each p is 1 or 2 and each A is as hereinbefore defined.

Preferred amines, for reasons of facility in undergoing the desired reaction with a reactive halide and excellent bleach stability of the brightener compounds obtained, are the 4-aminostilbenes (e.g., 4-amino-4'-methoxy-2,2'-stilbenedisulfonic acid,

the disodium salt thereof; 4-amino-4'-methoxy-2,2'-stilbenedisulfonamide,

4-amino-2-stilbenesulfonic acid,

and the sodium salt thereof) and the 4,4'-diaminostilbenes (e.g., 4,4'-diamino-2,2'-stilbenedisulfonic acid,

the disodium salt thereof; and 4,4'-diamino-2,2'-stilbenedisulfonamide).

Optical brighteners derived from amines of the present invention have the following structures:

wherein a, b, p, A, B and X have the meanings defined above.

Optical brighteners prepared from preferred amines have the structures:

and

wherein X, Y, W, M, R and R' are as hereinbefore defined.

The mono- (X is

and di- (Y is

X and W are

benzothiazolyl-S-dioxide compounds of the present invention can be prepared by reaction of an o-chlorosulfoaroylchloride and a suitable amine hereinbefore described. The reaction can be carried out at a temperature in the range of from 0° C. to 150° C.

The proportions of o-chlorosulfoaroyl chloride to fluorescent primary amine which can be employed are generally in the range of from 0.3:1 to 3:1 on a molar basis. In the case of the preparation of compounds of the formula

wherein x is zero, a range of about 0.3:1 to 1.5:1 is employed. Since the reaction is nearly quantitative, a molar proportion of 1:1 of o-chlorosulfoaroyl chloride to fluorescent primary amine is preferred. In the case of the preparation of compounds having a bis-structure, i.e., those wherein x in the above described formula is one, the molar proportion of o-chlorosulfoaroyl chloride to fluorescent primary amine employed is from 1.8:1 to 3:1, the ratio of 2:1 being preferred. When asymmetrical benzothiazolyl-S-dioxide derivatives are desired, two or more dissimilar o-chlorosulfoaroyl chlorides can be employed. Preferably, the o-chlorosulfoaroyl chlorides are sequentially reacted with the fluorescent amine.

While the reaction can be effected by reacting at a temperature of from 0° C. to 150° C., a preferred temperature range is about 50° C. to about 100° C. Reactions conducted at the lower temperature of the suitable range, i.e., at about 0° C. normally are effected in a period of time of about 24 hours. Conversely, reactions at about 100° C. require less time and may be effected in good yield in about 30 minutes.

The 2-benzisothiazolonyl-S-dioxide compounds of the invention are prepared in a polar organic solvent which is essentially non-reactive to either the o-chlorosulfoaroyl chloride or fluorescent amine employed in the reaction. The amount of solvent employed is an amount at least sufficient to dissolve the fluorescent amine, an amount of about three times the weight of amine employed being sufficient. Examples of suitable essentially non-reactive solvents which can be employed are water, alcohols, N,N-dialkyl low molecular weight amides such as dimethylformamide, cyclic ethers such as tetrahydrofuran and dioxane, aromatic hydrocarbons such as benzene and certain organic solvent-water mixtures such as dimethylformamide-water, e.g., dimethylformamide containing from about 1 to about 60% water on a volume/volume basis.

The mono- (X is

and di- (W, X and Y are

o-disulfophenylimidinyl compounds of the invention can be prepared by reaction of an aromatic o-disulfonyl chloride with a suitable amine hereinbefore described. The reaction can be carried out at a temperature in the range of 0° C. to 150° C. by reacting a 1,2-di(halosulfonyl) benzene with a fluorescent aromatic primary amine having the aforescribed spectral characteristics. The proportions of 1,2 - di(halosulfonyl)benzene to fluorescent primary amine which can be employed are generally in the range of 0.3:1 to 3:1 on a molar basis. The proportions of reactants employed to prepare compounds of the formula

wherein x is zero or one, will vary as in the case of reaction of an o-chlorosulfoaroyl chloride and a fluorescent primary amine described hereinbefore. Reaction can be effected at a temperature of from 0° C. to 150° C. A preferred temperature range is from 40° C. to 70° C.

The o-disulfophenylimidinyl compounds of the invention are prepared in water or a polar organic solvent which is essentially non-reactive to either the 1,2-di(halo-sulfonyl)benzene or fluorescent amine employed in the reaction. Suitable solvents and proportions thereof are described hereinbefore.

The mono- (X is $-\text{CH}_2-$) and di- (Y is

X and W are $-\text{CH}_2-$) benzothiazolyl-S-dioxide compounds of the invention can be prepared by reaction of a chloromethylaryl-o-sulfonyl chloride with a suitable amine hereinbefore described. The reaction can be carried out at a temperature in the range of 0° C. to 150° C. The proportion of chloromethylaryl-o-sulfonyl chloride to fluorescent primary amine which can be employed will vary within the range of 0.3:1 to 3:1 on a molar basis. The proportions of reactants employed to prepare compounds of the formula

wherein x is zero or one, will vary as in the case of reactions hereinbefore described. Reaction can be effected by reacting at a temperature of from 0° C. to 150° C. A preferred temperature range is from 20° C. to 60° C.

Generally, benzisothiazolyl-S-dioxide compounds of the present invention can be prepared in water, or in a polar organic solvent hereinbefore described. A preferred solvent is water.

The preparation of the optical brighteners of the invention is accompanied by formation of hydrochloric acid by-product. This acid can be neutralized in a conventional manner by addition of a suitable base, e.g., sodium carbonate, sodium bicarbonate, sodium hydroxide, triethylamine, or pyridine to the reaction product. Preferred herein is sodium bicarbonate.

The optical brighteners of the present invention exhibit remarkable stability in the presence of hypochlorite bleach. While applicants do not wish to be bound by any theory as to the nature of such stability, it is believed that the stability is due at least in part to the presence of essential moieties of the formula

and to the absence of a free hydrogen attached to a nitrogen atom. These moieties, named herein as substituents on a fluorescent stilbene or coumarin nucleus, e.g., 2-benzisothiazolonyl-S-dioxide

o-disulfophenylimidinyl

or 2-benzisothiazolyl-S-dioxide ($X=—CH_2—$), provide resistance to the harmful effects of hypochlorite bleaches and resulting loss of fluorescence. Other fluorescent aromatic amines can likewise be rendered resistant to degradative attack by hypochlorite bleaching compounds. Examples of such chromophoric amines are 5-amino-1,8-naphthalenecarboximides, 2-aminonaphthalenes, 3-amino-2,5-diaryl pyrroles and the like.

Specific examples of optical brightener compounds of the invention include the following:

- (1) 3-phenyl-7-(2-benzisothiazolyl-S-dioxide)coumarin
- (2) 3-phenyl-7-(2'-methyl-*o*-disulfophenylimidinyl)coumarin
- (3) 3-phenyl-7-(2-methyl-*o*-disulfophenylimidinyl)coumarin
- (4) 4-(2-benzisothiazolonyl-S-dioxide)-4'-methylstilbene
- (5) 4-(2-benzisothiazolonyl-S-dioxide)-4'-methoxy-stilbene
- (6) sodium 4-(2-benzisothiazolonyl-S-dioxide)-4'-stilbenesulfonate
- (7) 4-*o*-disulfophenylimidinyl-4'-phenylstilbene
- (8) 4-*o*-disulfophenylimidinyl-3-methoxy-4'-methyl-stilbene
- (9) 4-(2,2-chlorobenzisothiazolonyl-S-dioxide)-4'-(2,2-methylbenzisothiazolonyl-S-dioxide)-2,2'-stilbenedisulfonic acid
- (10) disodium 4,4'-di-*o*-disulfophenylimidinyl-2,2'-stilbenedisulfonate
- (11) 4,4'-di(2-benzisothiazolonyl-S-dioxide)-2,2'-stilbenedisulfonamide
- (12) 4-(2-benzisothiazolonyl-S-dioxide)-4'-(2-2-chlorobenzisothiazolonyl-S-dioxide)-2,2-stilbene-disulfonamide
- (13) disodium 4,4'-di(2-benzisothiazolonyl-S-dioxide)-6,6'-dichloro-2,2'-stilbenedisulfonate
- (14) disodium 4,4'-di(2-benzisothiazolonyl-S-dioxide)-3,5-dimethoxy-2,2'-stilbenedisulfonate
- (15) disodium 4,4'-bis(6-methoxy-2-benzisothiazolonyl-S-dioxide)-2,2'-stilbenedisulfonate
- (16) sodium 4-benzisothiazolyl-S-dioxide-2-stilbene-sulfonate

The optical brightener compounds of the present invention can be employed for the optical brightening of a wide variety of natural and synthetic materials. Natural materials include organic fibrous materials such as silk and wool. Synthetic fibers include such materials as polyester, polyacrylonitrile, polyamide, acetylated polyvinyl alcohol and polyolefin and cellulose acetate fibers. The brightener compounds of the invention provide excellent brightening and light fastness and can be employed in aqueous or solvent containing brightening compositions. These compositions can contain bleaching components such as hypochlorites without substantial loss of fluorescence.

The optical brighteners of the present invention can be incorporated into polymeric melts and processed to a variety of products including synthetic fibers. Alternatively, they can be applied to a substrate by application of a solution to the surface of a polymeric substrate.

The treatment of fibrous materials can be carried out by immersion of the fibrous materials in an aqueous dispersion of the optical brightening compound of the invention and a surface active agent. Suitable surface active agents include anionic or nonionic compounds such as alkylbenzenesulfonic acid, the condensation product of naphthalenesulfonic acid and formaldehyde or polyoxyethylene alkylether and the like. The fibrous material is immersed in the aqueous dispersion of brightener at a temperature of from 50° C. to 130° C. depending on the kind of fibrous material treated. The fibrous material is normally dried by heating at a temperature of from 160° C. to 220° C. for a time of from 0.5 to 2 minutes.

The brightener compounds of the invention can also be employed in laundry detergent compositions to provide an improved appearance to laundered goods. When so employed they range from 0.01% to 3% of the detergent composition. A preferred amount of brightener is from 0.5% to 1.5%. In addition to these brightener compounds, the laundry detergent compositions of the invention comprise at least 10% of a mixture of an organic detergent and an alkaline builder salt in a ratio in the range of from 5:1 to 1:20, preferably from 2:1 to 1:10. This mixture can be as much as the balance of the composition. The organic detergent compounds and alkaline builder salts are more fully described below.

ORGANIC DETERGENTS

The organic detergent compounds which can be utilized in the detergent compositions of this invention are the following:

(a) Water-soluble soaps.—Examples of suitable soaps for use in this invention are the sodium, potassium, ammonium and alkanolammonium (e.g. mono-, di-, and triethanolammonium) salts of higher fatty acids ($C_{10}-C_{22}$). Particularly useful are the sodium and potassium salts of the mixtures of fatty acids derived from coconut oil and tallow, i.e., sodium and potassium tallow and coconut soaps.

(b) Anionic synthetic non-soap detergents.—A preferred class can be broadly described as the water-soluble salts, particularly the alkali metal salts, of organic, sulfuric acid reaction products having in their molecular structure an alkyl radical containing from about 8 to about 22 carbon atoms and a radical selected from the group consisting of sulfonic acid and sulfuric acid ester radicals. (Included in the term alkyl is the alkyl portion of higher acyl radicals.) Important examples of these anionic synthetic detergents are the sodium or potassium alkyl sulfates, especially those obtained by sulfating the higher alcohols (C_8-C_{18} carbon atoms) produced by reducing the glycerides of tallow or coconut oil; sodium or potassium alkylbenzenesulfonates, in which the alkyl group can be a straight or branched chain and contains from about 9 to about 15 carbon atoms, preferably about 12-14 carbons; sodium alkyl glyceryl ether sulfonates, especially those ethers of the higher alcohols derived from

tallow and coconut oil; sodium coconut oil fatty acid monoglyceride sulfates and sulfonates; sodium or potassium salts of sulfuric acid esters of the reaction product of one mole of a higher fatty alcohol (e.g., tallow or coconut oil alcohols) and about 1 to 6 moles of ethylene oxide; sodium or potassium alkyl phenol ethylene oxide ether sulfates, with 1 to 10 units of ethylene oxide per molecule and wherein the alkyl radicals contain from 8 to 12 carbon atoms; the reaction product of fatty acids esterified with isethionic acid and neutralized with sodium hydroxide where, for example, the fatty acids are derived from coconut oil; sodium or potassium salts of fatty acid amide of a methyl tauride in which the fatty acids, for example, are derived from coconut oil; sodium and potassium salts of SO_3 -sulfonated $\text{C}_{10}-\text{C}_{24}$ α -olefins.

(c) Nonionic synthetic detergents.—One class of nonionic detergents can be broadly defined as compounds produced by the condensation of alkylene oxide groups (hydrophilic in nature) with an organic hydrophobic compound, which may be aliphatic or alkyl aromatic in nature. The length of the hydrophilic or polyoxyalkylene radical which is condensed with any particular hydrophobic group can be readily adjusted to yield a water-soluble compound having the desired degree of balance between hydrophilic and hydrophobic elements. A second class of nonionic detergents comprises higher fatty amides. A third class of nonionic detergents has semi-polar characteristics. These three classes can be defined in further detail as follows:

(1) One class of nonionic synthetic detergents is marketed under the trademark of "Pluronic." These detergent compounds are formed by condensing ethylene oxide with a hydrophobic base formed by the condensation of propylene oxide with propylene glycol. The hydrophobic portion of the molecule which, of course, exhibits water insolubility, has a molecular weight of from about 1500 to 1800. The addition of polyoxyethylene radicals to this hydrophobic portion tends to increase the water solubility of the molecule as a whole and the liquid character of the product is retained up to the point where the polyoxyethylene content is about 50% of the total weight of the condensation product.

(2) Alkylphenol-polyethylene oxide condensates are condensation products of alkyl phenols having an alkyl group containing from about 6 to 12 carbon atoms in either a straight chain or branched chain configuration with ethylene oxide, the said ethylene oxide being present in amounts equal to 5 to 25 moles of ethylene oxide per mole of alkyl phenol. The alkyl substituent in such compounds may be derived from polymerized propylene, diisobutylene, octene, or nonene, for example.

(3) Nonionic synthetic detergents can be derived from the condensation of ethylene oxide with the product resulting from the reaction of propylene oxide and ethylene diamine and include compounds containing from about 40% to about 80% polyoxyethylene by weight and having a molecular weight of from about 5,000 to about 11,000. Such compounds result from the reaction of ethylene oxide with a hydrophobic base constituted of the reaction product of ethylene diamine and excess propylene oxide, said base having a molecular weight of the order of 2,500 to 3,000.

(4) Other nonionic detergents include condensation products of aliphatic alcohols having from 8 to 22 carbon atoms, in either straight chain or branched chain configuration, with ethylene oxide, e.g., a coconut alcohol-ethylene oxide condensate having from 5 to 30 moles of ethylene oxide per mole of coconut alcohol.

(5) The ammonia, monoethanol and diethanol amides of fatty acids having an acyl moiety of from about 8 to about 18 carbon atoms are useful nonionic detergents. These acyl moieties are normally derived from naturally occurring glycerides, e.g., coconut oil, palm oil, soybean oil and tallow, but can be derived synthetically, e.g., by

the oxidation of petroleum, or by hydrogenation of carbon monoxide by the Fischer-Tropsch process.

(6) Semi-polar nonionic detergents include long chain tertiary amine oxides corresponding to the following general formula

wherein R^1 is an alkyl radical of from about 8 to about 18 carbon atoms, R^2 and R^3 are each methyl, ethyl or hydroxyethyl radicals, R^4 is ethylene, and n ranges from 0 to about 10. The arrow in the formula is a conventional representation of a semi-polar bond. Specific examples of amine oxide detergents include dimethyldodecylamine oxide and bis-(2-hydroxyethyl) dodecylamine oxide.

(7) Other semi-polar nonionic detergents include long chain tertiary phosphine oxides corresponding to the following general formula $\text{RR}'\text{R}''\text{P}\rightarrow\text{O}$ wherein R is an alkyl, alkenyl or monohydroxyalkyl radical containing from 10 to 20 carbon atoms and R' and R'' are each alkyl or monohydroxyalkyl groups containing from 1 to 3 carbon atoms. The arrow in the formula is a conventional representation of a semi-polar bond. Examples of suitable phosphine oxides are found in U.S. Pat. 3,304,263 which issued Feb. 14, 1967, and include: dimethyldodecylphosphine oxide and dimethyl-2-hydroxydodecyl phosphine oxide.

(d) Ampholytic synthetic detergents can be broadly described as derivatives of aliphatic secondary and tertiary amines, in which the aliphatic radical can be straight chain or branched alkyls and wherein one of the aliphatic substituents contains from about 8 to 18 carbon atoms and one contains an anionic water solubilizing group, e.g., carboxy, sulfo, sulfato, phosphate, or phosphono. Examples of compounds falling within this definition are sodium-3-dodecylaminopropionate and sodium-3-dodecylaminopropane sulfonate.

(e) Zwitterionic synthetic detergents can be broadly described as derivatives of aliphatic quaternary ammonium, phosphonium and sulfonium compounds, in which the aliphatic radical can be straight chain or branched alkyl, and wherein one of the aliphatic substituents contains from about 8 to 24 carbon atoms and one contains an anionic water solubilizing group, e.g., carboxy, sulfo, sulfato, phosphate or phosphono. Examples of compounds falling within this definition are 3-(N,N-dimethyl-N-hexadecylammonio)propane-1-sulfonate and 3-(N,N-dimethyl-N-hexadecylammonio)-2-hydroxy propane-1-sulfonate which are preferred for their cool water detergency characteristics. See for example, Snoddy et al., Canadian Pat. 708,148.

These soap and non-soap anionic, nonionic, ampholytic and zwitterionic detergent compounds can be used singly or in combination. The above examples are merely illustrations of the numerous suitable detergents. Other organic detergent compounds can also be used.

BUILDER SALTS

(f) The detergent compositions of this invention also contain water-soluble, builder salts either of the organic or inorganic types.

Examples of suitable water-soluble, inorganic alkaline detergency builder salts are alkali metal carbonates, borates, phosphates, polyphosphates, bicarbonates, silicates and sulfates. Specific examples of such salts are sodium and potassium tetraborates, perborates, bicarbonates, carbonates, tripolyphosphates, pyrophosphates, orthophosphates and hexametaphosphates.

Examples of suitable organic alkaline detergency builder salts are: (1) Water-soluble aminopolyacetates, e.g., sodium and potassium ethylenediaminetetraacetates, nitrolotriacetates and N-(2-hydroxyethyl)-nitrilo diacetates; (2) Water-soluble salts of phytic acid, e.g., sodium and potassium phytates—see U.S. Pat. 2,739,942; (3)

Water-soluble polyphosphonates, including specifically, sodium, potassium and lithium salts of ethane-1-hydroxy-1,1-diphosphonic acid, sodium, potassium and lithium salts of methylene diphosphonic acid, sodium, potassium and lithium salts of ethylene diphosphonic acid, and sodium, potassium and lithium salts of ethane-1,1,2-triphosphonic acid. Other examples include the alkali metal salts of ethane-2-carboxy-1,1-diphosphonic acid, hydroxymethane-diphosphonic acid, carbonyldiphosphonic acid, ethane-1-hydroxy-1,1,2-triphosphonic acid, ethane-2-hydroxy-1,1,2-triphosphonic acid, propane - 1,1,3,3 - tetraphosphonic acid, propane-1,1,2,2-tetraphosphonic acid, and propane-1,2,2,3-tetraphosphonic acid; (4) Water-soluble salts of polycarboxylate polymers and copolymers as described in the patent of Francis L. Diehl, U.S. Pat. 3,308,067 issued March 7, 1967. Specifically, a detergent builder material comprising a water-soluble salt of a polymeric aliphatic polycarboxylic acid having the following structural relationships as to the position of the carboxylate groups and possessing the following prescribed physical characteristics: (a) a minimum molecular weight of about 350 calculated as to the acid form; (b) an equivalent weight of about 50 to about 80 calculated as to acid form; (c) at least 45 mole percent of the monomeric species having at least two carboxyl radicals separated from each other by not more than two carbon atoms; (d) the site of attachment to the polymer chain of any carboxy-containing radical being separated by not more than three carbon atoms along the polymer chain from the site of attachment of the next carboxyl-containing radical. Specific examples are polymers of itaconic acid, aconitic acid, maleic acid, mesaconic acid, fumaric acid, methylene malonic acid, and citraconic acid and copolymers with themselves and other compatible monomers such as ethylene.

Mixtures of organic and/or inorganic builders can be used and are generally desirable. One such mixture of builders is disclosed in Canadian Pat. 755,038 of Burton H. Gedge, e.g., ternary mixtures of sodium tripolyphosphate, trisodium nitrilotriacetate and trisodium ethane-1-hydroxy-1,1-diphosphonate. The above described builders can also be utilized singly in this invention.

The preferred builders are sodium tripolyphosphate and sodium nitrilotriacetate, alone or in admixture. The preferred organic detergents are the anionic sulfate and sulfonates. The detergent compositions preferably provide pHs in the range of about 8.5 to 11.5.

The laundry detergent compositions of this invention can contain, if desired, in addition to the brightener, organic detergent and builder, any of the usual additives for such compositions which make them more attractive or effective. For example, perfumes, dyes, proteolytic enzymes, corrosion inhibitors, oxygen and chlorine bleaches, soil redeposition agents and other brighteners can be used. Diluents such as water, moisture and sodium sulfate can also be used to make up any balance of a composition comprising brightener, organic detergent and alkaline builder salt.

The optical brighteners of the invention are stable to attack by hypochlorite compounds. Accordingly, they are advantageously employed in laundry compositions which contain from 0.5% to 25%, usually 3-17%, of an active-chlorine containing bleaching compound. Examples of such compounds are: dichlorocyanuric acid; 1,3-dichloro-5,5-dimethyl hydantoin; N,N'-dichlorobenzoylene urea; paratoluene sulfondichloroamide; trichloromelamine; N-chloroameline; N-chlorosuccinimide; N,N'-dichloroazodicarbonamide; N-chloroacetyl urea; N,N'-dichlorobiuret; chlorinated dicyandiamide; sodium hypochlorite; calcium hypochlorite; lithium hypochlorite; chlorinated trisodium phosphate. Preferred compounds are dichlorocyanurates, i.e., dichlorocyanuric acid and the sodium and potassium salts thereof.

In other embodiments of the present invention the optical brighteners are employed in aqueous and granular bleach compositions. In general, aqueous bleach composi-

tions are prepared by dissolving or dispersing an optical brightener in an aqueous solution of alkali metal hypochlorite bleach. The optical brighteners of the present invention are readily soluble in aqueous hypochlorite solution and remain stable over an extended period of time so that they can be successfully packaged, shipped and stored without rendering ineffective the whitening action of the optical brightener or the oxidizing action of the bleach. Liquid bleach compositions prepared in accordance with the present invention are characterized by a pH ranging from 10.5 to 13.0 and consist essentially of from 1.0% to 10% alkali metal hypochlorite bleach, from 0.002% to 2% of the optical brightener and the balance water.

Preferred hypochlorite bleach-containing compositions contain the alkali metal hypochlorite bleach component in an amount of from 1% to 10%, preferably from 3% to 7%, with about 5.2% being especially preferred.

The bleach component can be any one of the alkali metal hypochlorites. Examples of such useful bleaches are sodium hypochlorite, potassium hypochlorite, lithium hypochlorite, and the like. However, sodium hypochlorite is highly preferred because of its superior properties and its ready availability.

The optical brightener is present in the liquid bleach compositions of this invention in an amount ranging from 0.002% to 2.0%, preferably from 0.01% to 0.1% with about 0.05% being especially preferred. Dispersible polymeric stabilizing or suspending agents can also be employed. Suitable examples are described in U.S. Pat. No. 3,393,153 to Zimmerer *et al.*, issued July 16, 1968.

The bleach stable brighteners of the present invention are capable of retaining their whitening and brightening effects even after exposure to aqueous 1-10% hypochlorite-containing bleach solutions for extended periods of time, e.g., several weeks of storage. The bleach stability which is normally ascribed to conventional optical brighteners is commonly understood to mean that these optical brighteners are not ineffective when exposed to dilute solutions of bleach for limited periods of time, e.g., at washing machine conditions where the hypochlorite bleach is present in aqueous solutions at about 0.02% hypochlorite level for up to 20 to 30 minutes. In contradistinction to the bleach compatibility commonly understood in the art, the compatibility of the presently claimed optical brighteners is such that they retain their fluorescing effects after exposure to hypochlorite bleach concentrations much higher than normally found in the course of the laundering process.

The desirable bleach compatibility of the optical brighteners of the present invention is employed to advantage in the use of these brighteners in liquid hypochlorite or granular bleach-containing compositions. These compositions normally comprise from 1% to 99% of an active chlorine-containing bleaching compound which is capable of evolving hypochlorite upon contact with water and from 0.005% to 10% of the optical brightener of the present invention. Preferably the granular bleaching compositions of the invention contain from 1% to 80% of the active chlorine-containing bleaching compound, from 2% to 25% of an organic detergent and from 5% to 60% of an alkaline builder salt, said bleaching compounds and builder salts being those hereinbefore described.

The granular-bleach compositions of this invention can contain, if desired, in addition to the bleaching compounds, any of the usual additives for such compositions which make them more attractive or effective, for example, perfumes, dyes, proteolytic enzymes, corrosion inhibitors, other chlorine bleaches, soil redeposition agents and other brighteners may be used.

These granular bleach compositions have a pH ranging from about 8 to 12 and upon dissolution in water evolve active hypochlorite chlorine for the effective bleaching of cellulosic fabrics.

Preparations of exemplary optical brighteners of this invention are described as follows:

EXAMPLE I

Preparation of disodium 4,4'-(2-benzisothiazolonyl-S-dioxide)-2,2'-stilbenedisulfonate

A solution of 4.78 parts of 2-chlorosulfonylbenzoyl chloride (0.02 mole), 4.14 parts of disodium 4,4'-diamino-2,2'-stilbenedisulfonate (0.01 mole), 4.86 parts triethylamine and 100 parts dimethylformamide was heated on a steam bath (80-90° C.) for 3½ hours. The reaction was conducted in a 200-ml. flask equipped with magnetic stirrer bar, reflux condenser and calcium chloride drying tube. The reaction mixture was distilled under the pressure of a water aspirator and at a bath temperature of 50° C. for two hours to yield a brown-colored residue. The residue was stirred with 15 ml. water and filtered through a sintered glass funnel. The resulting product was dried to yield 7.5 parts of a light tan-colored product which was disodium 4,4'-(2-benzisothiazolonyl-S-dioxide)-2,2'-stilbenedisulfonate.

Infrared spectra (IR), nuclear magnetic resonance (NMR) and ultraviolet (UV) analyses confirmed the structure of the resulting product. NMR spectra indicated a complex aromatic multiplet centered at 1.7 τ . The UV absorption λ_{max} was 340 nm. and the fluorescence λ_{max} was 420 nm.

Similar results are obtained when 4-methoxy-4'-amino-2,2'-stilbenedisulfonamide or dipotassium 4,4'-diamino-6,6' - dimethoxy-2,2'-stilbenedisulfonate is employed in place of disodium 4,4'-diamino-2,2'-stilbenedisulfonate in that the following optical brighteners are obtained: 4-methoxy-4'-(2-benzisothiazolonyl-S-dioxide) - 2,2' - stilbenedisulfonamide or dipotassium 4,4'-di(2-benzisothiazolonyl-S-dioxide)-6,6'-dimethoxy - 2,2' - stilbenedisulfonate.

Similar results are obtained when

3-methyl-2-chlorosulfonyl-benzoyl chloride; 4-ethoxy-2-chlorosulfonyl-benzoyl chloride; 3-naphthyl-2-chlorosulfonyl-benzoyl chloride; 5-methylsulfonyl-2-chlorosulfonyl-benzoyl chloride; 5-ethoxymethyl-2-chlorosulfonyl-benzoyl chloride; 3-(1,4,7-trioxanonyl)-2-chlorosulfonyl-benzoyl chloride; 3-trifluoromethyl-2-chlorosulfonyl-benzoyl chloride; 4-acetyl-2-chlorosulfonyl-benzoyl chloride; 4-cyano-2-chlorosulfonyl-benzoyl chloride; and 4-(1,2,3-trihydroxypropyl)-2-chlorosulfonyl-benzoyl chloride

are employed in place of an equimolar amount of 2-chlorosulfonyl-benzoyl chloride in that the following optical brightener compounds are formed:

disodium 4,4'-(9-methyl-2-benzisothiazolonyl-S-dioxide)-2,2'-stilbenedisulfonate; disodium 4,4'-(8-ethoxy-2-benzisothiazolonyl-S-dioxide)-2,2'-stilbenedisulfonate; disodium 4,4'-(9-(1,4,7-trioxanonyl)-2-benzisothiazolonyl-S-dioxide)-2,2'-stilbenedisulfonate; disodium 4,4'-(9-trifluoromethyl-2-benzisothiazolonyl-S-dioxide)-2,2'-stilbenedisulfonate; disodium 4,4'-(8-acetyl-2-benzisothiazolonyl-S-dioxide)-2,2'-stilbenedisulfonate; disodium 4,4'-(8-cyano-2-benzisothiazolonyl-S-dioxide)-2,2'-stilbenedisulfonate; and disodium 4,4'-(8-(1,2,3-trihydroxypropyl)-2-benzisothiazolonyl-S-dioxide)-2,2'-stilbenedisulfonate.

EXAMPLE II

Preparation of disodium 4,4'-(*o*-disulfophenylimidinyl)-2,2'-stilbenedisulfonateThe apparatus of Example I was employed. Two parts (7.57×10^{-3} moles) of 1,2-di(chlorosulfonyl)benzene, 1.57 parts (3.78×10^{-3} moles) of disodium 4,4'-diamino-2,2'-stilbenedisulfonate, 1.27 parts of sodium bicarbonate and 10 parts distilled water were added to the reaction vessel. The reaction mixture was heated on a steam bath for 14 hours (80-90° C.). The resulting solution, yellow-colored, was cooled to 0° C. and filtered through a sintered glass funnel to yield 0.3 part disodium 4,4'-(*o*-disulfophenylimidinyl)stilbenedisulfonate, the desired product. An additional 2.5 parts of the desired product were isolated from the aqueous filtrate by concentrating the filtrate to dryness, extracting with 100 ml. of boiling methanol, filtering, recrystallizing by addition of 100 ml. diethylether and filtering the solid product.

Calc.: C, 33.7; H, 3.03; N, 3.02.

Found: C, 33.0; H, 2.7; N, 3.0.

IR, NMR and UV analyses confirmed the structure of the resulting product, NMR spectra indicated a complex multiplet centered at 1.9 τ . The UV absorption λ_{max} was 314 nm. and the fluorescence λ_{max} was 425 nm.

Similar results are obtained when

2-methyl-4,4'-diamino-2'-stilbenesulfonamide; 2-ethoxy-4,4'-diamino-2'-stilbenesulfonamide; 2,4-dichloro-4'-amino-2'-stilbenesulfonamide; and disodium 4,4'-diamino-6-methoxy-2,2'-stilbenedisulfonate are employed in place of 4,4'-diamino-2,2'-stilbenedisulfonate in that the following optical brighteners are obtained:

4,4'-(*o*-disulfophenylimidinyl)-2-methyl-stilbenesulfonamide; 4,4'-(*o*-disulfophenylimidinyl)-2-ethoxy-stilbenesulfonamide; 2,4-dichloro-4'-(2-benzisothiazolonyl-S-dioxide)-2'-stilbenesulfonamide; and disodium 4,4'-di(2-benzisothiazolonyl-S-dioxide)-6-methoxy-2,2'-stilbenedisulfonate.

EXAMPLE III

Preparation of disodium 4,4'-(2-benzisothiazolonyl-S-dioxide)-2,2'-stilbenedisulfonate

The apparatus of Example I was employed. 4.02 parts of a mixture of α -bromo- α -toluenesulfonyl chloride and α -chloro- α -toluenesulfonyl chloride (prepared by refluxing a solution of 95.5 parts α -toluenesulfonyl chloride, 120 parts N-bromosuccinimide, 3 parts benzoyl peroxide and 600 ml. carbon tetrachloride for 8 hours; cooling the reaction mixture; removing solids by filtration; washing with carbon tetrachloride; distilling at water aspirator pressure and a bath temperature of 50° C.; and distilling the residue to provide a colorless oil of B.P. 124-130° C. at 0.6 mm. pressure), 3.48 parts disodium 4,4'-diamino-2,2'-stilbenedisulfonate, 3.78 parts sodium bicarbonate and 25 parts water were heated on a steam bath 80-90° C. for 48

hours. The reaction mixture was cooled to 0° C. and filtered through a sintered glass funnel to provide 2.2 parts of the desired product, 4,4' - (2 - benzisothiazolyl-S-dioxide)-2,2'-stilbenedisulfonate. An additional 2.0 parts of product were recovered from the aqueous filtrate by extraction with methanol and re-crystallization with diethyl-ether.

Calc.: C, 42.6; H, 3.42; N, 3.42; S, 16.25.
Found: C, 42.58; H, 3.44; N, 3.03; S, 16.9.

IR, NMR and UV analyses confirmed the structure of the resulting product. NMR spectra indicated a singlet at 4.55 τ and a complex multiplet centered at 1.75 τ . The UV absorption λ_{max} was 332 nm. and the fluorescence λ_{max} was 409 nm.

Similar results are obtained when

sodium 4,4'-diamino-2-methylsulfonyl-2'-stilbene-sulfonate;
sodium 4,4'-diamino-5-ethoxymethyl-2'-stilbenesulfonate;
sodium 4,4'-diamino-5-trifluoromethyl-2'-stilbene-sulfonate;
sodium 4,4'-diamino-2-propionyl-2'-stilbenesulfonate

are employed in place of 4,4'-diamino-2,2'-stilbenedisulfonate in that the following optical brighteners are obtained:

4,4'-(2-benzisothiazolyl-S-dioxide)-2-methylsulfonyl-2'-stilbenedisulfonate;
4,4'-(2-benzisothiazolyl-S-dioxide)-5-ethoxymethyl-2'-stilbenedisulfonate;
4,4'-(2-benzisothiazolyl-S-dioxide)-5-trifluoromethyl-2'-stilbenedisulfonate;
4,4'-(2-benzisothiazolyl-S-dioxide)-2-propionyl-2'-stilbenedisulfonate; and
4,4'-(2-benzisothiazolyl-S-dioxide)-2-cyano-2'-stilbenedisulfonate.

EXAMPLE IV

(a) Preparation of 4,4'-bis(2-benzisothiazolyl-S-dioxide)-2,2'-stilbenedisulfonyl chloride

A suspension of 8.72 parts of disodium 4,4'-(2-benzisothiazolyl-S-dioxide) - 2,2' - stilbenedisulfonate, 20 parts thionyl chloride and 300 parts of dimethylformamide was stirred at ambient temperature of 15 minutes. The resulting solid product was filtered, washed with water, acetone and dried to give 8.63 parts of 4,4'-(2-benzisothiazolyl-S-dioxide)-2,2'-stilbenedisulfonyl chloride. NMR, IR and elemental analyses confirmed formation of the desired compound.

Calc.: C, 47.3; H, 2.83; N, 3.94; Cl, 9.97.
Found: C, 47.2; H, 3.2; N, 4.1; Cl, 10.5.

(b) Preparation of 4,4'-(2-benzisothiazolyl-S-dioxide)-2,2'-stilbenedisulfonamide

A suspension of 7.1 (0.01 mole) parts of 4,4'-(2-benzisothiazolyl-S-dioxide) - 2,2' - stilbenedisulfonyl chloride prepared as described in part (a) above, 5 parts of 28% ammonium hydroxide, 10 parts pyridine and 100 parts of dimethyl formamide was stirred at ambient temperature for three hours. The solid was filtered, washed with water, acetone and dried to give 5.9 parts of 4,4'-(2-benziso-

thiazolyl-S-dioxide)-2,2'-stilbenedisulfonamide. NMR, IR, UV and elemental analyses confirmed the formation of the desired compound. The UV λ_{max} was 332 nm. and the fluorescence λ_{max} was 425 nm.

5 (c) Preparation of 4,4'-(2-benzisothiazolyl-S-dioxide)-2,2'-stilbenedisulfonyl amide

4,4'-(2-benzisothiazolyl-S-dioxide) - 2,2' - stilbenedisulfonyl chloride prepared in part (a) above was reacted with morpholine, diethanolamine, glucosamine, aniline, diethylamine and 2-ethylaminoethanol in the manner described in part (b) above. In each instance an equimolar amount of amine was employed in place of the ammonium hydroxide of part (b). The resulting optical brightener compounds conforming to the formula

20 and the definitions of R and R' are described, respectively, in Table 1 as follows:

TABLE 1

		U.V. ab-sorption, $\lambda_{\text{max.}}, \text{nm.}$	Fluorescence $\lambda_{\text{max.}}, \text{nm.}$

EXAMPLE V

(a) Preparation of disodium 4-amino-4'-(1-phthalimidinyl)-2,2'-stilbenedisulfonate

50 A solution of 1.33 parts (0.01 mole) of phthalide, 4.68 parts (0.01 mole) of disodium 4,4'-diaminostilbene-2,2'-disulfonate, 0.02 parts of N,N-dimethyldodecylamine and 30 parts of ethylene glycol was heated on the steam bath (90-95° C.) for 18 hours. The reaction was conducted in a 100-ml. one-necked flask fitted with a reflux condenser and calcium chloride drying tube. The reaction mixture was cooled to 20° C., 300 parts of ethanol were added and the solution was filtered. Addition of 300 parts of diethylether to the filtrate followed by filtration yielded 3.0 parts of a light-tan solid which was disodium 4-amino-4'-(1-phthalimidinyl)-2,2'-stilbenedisulfonate. IR, NMR and UV analyses confirmed the structure of the resulting product.

Calc.: C, 40.3; H, 4.57; N, 4.27.
Found: C, 40.26; H, 4.65; N, 4.53.

NMR spectra indicated a singlet at 4.85τ , triplet at 3.55τ and an aromatic multiplet centered at about 1.7τ .

(b) Preparation of disodium 4-(2-benzisothiazolyl-S-dioxide)-4'-(1-phthalimidinyl)-2,2'-stilbenedisulfonate.

A solution of 1.9 parts of α -bromo- α -toluenesulfonyl chloride with α -chloro- α -toluenesulfonyl chloride (as prepared in Example III), 3.77 parts of disodium 4-amino-4'-(1-phthalimidinyl)-2,2'-stilbenedisulfonate and 1.8 parts of sodium bicarbonate in 20 parts of water was heated on a steam bath ($80-90^\circ\text{C}$) for 16 hours. The resulting solution was cooled to 0°C . and filtered to give 0.9 parts of the desired compound, disodium 4-(2-benzisothiazolyl-S-dioxide)-4'-(1-phthalimidinyl)-2,2'-stilbenedisulfonate. An additional 4.0 parts of the product were isolated from the aqueous filtrate. NMR, IR, UV and elemental analyses confirmed formation of the desired optical brightener.

Calc.: C, 38.83; H, 4.89; N, 3.12.

Found: C, 38.35; H, 3.88; N, 3.14.

NMR spectra indicated a doublet at 4.75τ and a multiplet centered at 1.85τ . The UV absorption λ_{max} was 325 nm. and the fluorescence λ_{max} was 440 nm.

(c) Preparation of 4-(2-benzisothiazolyl-S-dioxide)-4'-(1-phthalimidinyl)-2,2'-distilbenesulfonyl chloride

A suspension of 3.0 parts of disodium 4-(2-benzisothiazolyl-S-dioxide)-4'-(1-phthalimidinyl)-2,2'-stilbenedisulfonate, prepared in Example V(b), 8.0 parts of thionyl chloride and 50 parts of dimethyl formamide was stirred at ambient temperature for 90 minutes. The solid was filtered, washed with water, then acetone, and dried to give 2.4 parts of 4-(2-benzisothiazolyl-S-dioxide)-4'-(1-phthalimidinyl)-2,2'-stilbenedisulfonyl chloride. NMR, IR and elemental analyses confirmed formation of the above compound.

(d) Preparation of 4-(2-benzisothiazolyl-S-dioxide)-4'-(1-phthalimidinyl)-2,2'-stilbenedisulfonamide

A suspension of 6.8 parts (0.01 mole) of 4-(2-benzisothiazolyl-S-dioxide)-4'-(1-phthalimidinyl) stilbene-2,2'-disulfonyl chloride, 5 parts of 28% ammonium hydroxide, 1 part pyridine and 10 parts of dimethyl formamide was stirred at ambient temperature for three hours. The solid was filtered, washed with water, then acetone, and dried to give 5.4 parts of 4-(2-benzisothiazolyl-S-dioxide)-4'-(1-phthalimidinyl)stilbene-2,2'-disulfonamide.

IR, NMR and UV analyses confirmed the structure of the resulting product. NMR spectra indicated a singlet at 4.89τ and 3.50τ and an aromatic multiplet centered at about 2.0τ . The UV absorption λ_{max} was 325 nm. and the fluorescence λ_{max} was 430 nm.

(e) Preparation of 4-(2-benzisothiazolyl-S-dioxide)-4'-(1-phthalimidinyl)-2,2'-distilbenesulfonamides

4 - (2 - benzisothiazolyl-S-dioxide) - 4' - (1-phthalim-

5 indinyl)-2,2'-distilbenesulfonyl chloride, from part (c) above, was reacted with morpholine, diethanolamine and aniline in place of the ammonium hydroxide in part (d) above. The compounds corresponding to the formula

and the definitions of R and R' are described, respectively, in Table 2 as follows:

TABLE 2

R: R'	U.V. absorption, λ_{max} , nm.	Fluorescence, λ_{max} , nm.

EXAMPLE VI

Preparation of sodium 4-(2-benzisothiazolonyl-S-dioxide)-2-stilbenesulfonate

The solution obtained by dissolving 2.39 parts (0.01 mole) of 2-chlorosulfonyl-benzoyl chloride, 3.1 parts (0.01 mole) of sodium 4-amino-2-stilbenesulfonate, and 1.1 parts of triethylamine and 100 parts of dimethyl formamide are heated in a 500-ml. one-necked flask equipped with a magnetic stirrer bar and reflux condenser. The reaction vessel is heated at a temperature of $80-90^\circ\text{C}$. for 16 hours. The reaction product is distilled under the pressure of a water aspirator and at a bath temperature of 50°C . to provide a solid residue which is washed with water, filtered and dried to provide the desired product, sodium 4-(2-benzisothiazolonyl-S-dioxide)-2-stilbenesulfonate. The compound is a bleach-stable optical brightener.

Similar results are obtained when 4-bromo-2-chlorosulfonylbenzoyl chloride; 4-methoxy-2-chlorosulfonyl-benzoyl chloride; and 4-methyl-2-chlorosulfonyl-benzoyl chloride are employed in place of α -chlorosulfonyl-benzoyl chloride in that the correspondingly substituted optical brightener compounds are obtained, respectively, as follows:

sodium 4-(8-bromo-2-benzisothiazolonyl-S-dioxide)-

2-stilbenesulfonate;

sodium 4-(8-methoxy-2-benzisothiazolonyl-S-dioxide)-

2-stilbenesulfonate;

sodium 4-(8-methyl-2-benzisothiazolonyl-S-dioxide)-

2-stilbenesulfonate.

Similar results are obtained when 1,2-di(chlorosulfonyl)benzene and 2-chloro- α -toluenesulfonate chloride are employed in lieu of 2-chlorosulfonyl-benzoyl chloride in that the following optical brightener compounds are ob-

tained: sodium 4-(*o*-disulfophenylimidinyl)-2-stilbenesulfonate; and sodium 4-(2-benzisothiazolyl)-2-stilbenesulfonate.

Similar results are obtained when the sodium 4-amino-2-stilbenesulfonate is replaced by 4-amino-4'-ethoxy-2,2'-stilbenedisulfonic acid; disodium 4-amino-4'-methoxy-2,2'-stilbenedisulfonate; 4-amino-4'-methoxy-2,2'-stilbenedisulfonamide; and 4-amino-2-stilbenesulfonic acid; in that the following bleach-stable optical brighteners are obtained:

sodium 4-(2-benzisothiazolonyl-S-dioxide)-2-stilbenesulfonate; 4-(2-benzisothiazolonyl-S-dioxide)-4'-ethoxy-2,2'-stilbenedisulfonic acid; disodium 4-(2-benzisothiazolonyl-S-dioxide)-4'-methoxy-2,2'-stilbenedisulfonamide, and 4-(2-benzisothiazolonyl-S-dioxide)-2-stilbenesulfonic acid.

EXAMPLE VII

Preparation of 3-phenyl-7-(*o*-disulfophenyl-imidinyl) coumarinThe solution obtained by adding 2.37 parts (0.01 mole) of 7-amino-3-phenylcoumarin to 2.75 parts (0.01 mole) of 1,2-di(chlorosulfonyl)benzene and 10 parts of water is heated on a steam bath (80-90° C.) for a period of 14 hours. The heating is conducted in a 50-ml. one-necked round-bottomed flask equipped with a reflux condenser. The resulting solution is cooled to 0° C. and filtered through a sintered glass funnel to provide the desired product, 3-phenyl-7-(*o*-disulfophenylimidinyl)coumarin. An additional portion of the desired product is isolated from the aqueous filtrate by concentrating the filtrate to dryness, extracting with methanol, recrystallizing with diethyl ether and filtering the product. The resulting compound is an optical brightener having bleach-compatibility properties.

Similar results are obtained when 7-amino-4-phenylcoumarin; 7-amino-5-chlorocoumarin; 7-amino-3-phenyl-8-methoxycoumarin; 7-amino-3-methylcoumarin; 7-amino-3,5,8-trimethoxycoumarin; 7-amino-3,5-diphenylcoumarin; 7-amino-3-phenyl-5-chloromethylcoumarin; 7-amino-5-(3',5',7'-trioxanonyl)-3-phenylcoumarin are employed in place of 7-amino-3-phenylcoumarin in that the following bleach-stable optical brightener compounds are formed:

7-(*o*-disulfophenylimidinyl)-4-phenyl coumarin; 7-(*o*-disulfophenylimidinyl)-5-chlorocoumarin; 7-(*o*-disulfophenylimidinyl)-3-phenyl-8-methoxycoumarin; 7-(*o*-disulfophenylimidinyl)-3-methylcoumarin; 7-(*o*-disulfophenylimidinyl)-3,5,8-trimethoxycoumarin; 7-(*o*-disulfophenylimidinyl)-3,5-diphenylcoumarin; 7-(*o*-disulfophenylimidinyl)-3-phenyl-5-chloromethylcoumarin; 7-(*o*-disulfophenylimidinyl)-5-(3',5',7'-trioxanonyl)-3-phenylcoumarin.

Similar results are obtained when the 1,2-di(chlorosulfonyl)benzene of Example VII is replaced with an equimolar amount of 2-chlorosulfonyl-benzoyl chloride or α -chloro- α -toluenesulfonyl chloride in that the resulting optical brightener compounds are 3-phenyl-7-(2-benzis-

thiazolonyl-S-dioxide)coumarin and 3-phenyl-7-(2-benzisothiazolonyl-S-dioxide)coumarin.

EXAMPLE VIII

(a) Preparation of disodium 4-amino-4'-phthalimidyl-2,2'-stilbenedisulfonate

The solution obtained by dissolving 4.14 parts (0.01 mole) of disodium 4,4'-diamino-2,2'-stilbenedisulfonate in 500 ml. of dimethylformamide (DMF) is added over a period of one hour to a stirred solution of 1.47 parts (0.011 mole) of phthalic anhydride dissolved in 200 ml. of DMF and maintained at 60° C. The reaction is conducted in a 1-liter flask equipped with a magnetic stirring bar and dropping funnel. After stirring for an additional hour at 60° C. the DMF is removed by a rotary evaporator. The product, disodium 4-amino-4'-phthalimidyl-2,2'-stilbenedisulfonate is crystallized from water and dried.

(b) Preparation of disodium 4-(2-benzisothiazolonyl-S-dioxide)-4'-phthalimidyl-2,2'-stilbenedisulfonate

The solution obtained by admixing 5.44 parts (0.01 mole) of the product of part (a) above, 2.39 parts (0.01 mole) of 2-chlorosulfonyl-benzoyl chloride, 1.01 parts of triethylamine and 100 parts of DMF is heated on a steam bath (80-90° C.) for 16 hours. The solution is heated in a 250-ml. one-necked round-bottomed flask equipped with a reflux condenser and a calcium chloride drying tube. Upon completion of the heating period, the solvent is distilled at water aspirator pressure and a bath temperature of 50° C. to provide a solid residue. The residue is washed with water and filtered through a sintered glass funnel and dried to provide the desired product, disodium 4-(2-benzisothiazolonyl-S-dioxide)-4-phthalimidyl-2,2'-stilbenedisulfonate.

EXAMPLE IX

(a) Preparation of disodium 4-amino-4'-(2-benzisothiazolonyl-S-dioxide)-2,2'-stilbenedisulfonate

A solution of 2.39 parts of 2-chlorosulfonyl-benzoyl chloride (0.01 mole), 4.14 parts of disodium 4,4'-diamino-2,2'-stilbenedisulfonate (0.01 mole), 1.01 parts of triethylamine and 100 parts dimethylformamide are heated on a steam bath (80-90° C.) for 16 hours. The reaction is conducted in a 250-ml. one-necked flask equipped with a reflux condenser and a calcium chloride drying tube. The reaction mixture is distilled at water aspirator pressure and at a bath temperature of 50° C. for three hours to

yield a solid residue. The residue is stirred with water and filtered through a sintered glass funnel. The resulting product is washed with acetone and dried to yield disodium 4-amino-4'-(2-benzisothiazolonyl - S - dioxide)-2,2'-stilbenedisulfonate.

(b) Preparation of disodium 4-(1-isoindolinyl)-4'-(2-benzisothiazolonyl-S-dioxide)-2,2'-stilbenedisulfonate

A suspension of 5.79 parts (0.01 mole) of disodium 4-amino-4'-(2-benzisothiazolonyl - S - dioxide)-2,2'-stilbenedisulfonate, prepared as described in Example IX(a), 2.64 parts (0.01 mole) of o-xylene dibromide, 0.84 part of sodium bicarbonate and 50 parts of water is heated on a steam bath (80-90° C.) for a period of 14 hours. The reaction is conducted in a 100-ml. flask fitted with a reflux condenser. The resulting solution is cooled to 0° C. and filtered through a sintered glass funnel to provide the desired product.

A bleach-stability test was performed to evaluate the bleach compatibility of the brighteners of the present invention in concentrated aqueous hypochlorite-containing solution.

A bleach-stability test was performed to evaluate the bleach compatibility of the brighteners of the present invention in concentrated aqueous hypochlorite-containing solution. Aqueous sodium hypochlorite solutions containing approximately 5.25% sodium hypochlorite and 0.5% of the compounds of Examples I to IV were formulated by dissolving the optical brightener in the aqueous hypochlorite-containing solutions. The resulting solutions were visually examined periodically under ultraviolet light for fluorescence. The solutions continued to exhibit strong fluorescence after a storage period of four hours indicating a high degree of stability under extremely adverse hypochlorite degradative conditions.

The detergent (laundering and brightening) compositions of this invention are exemplified by the following examples which describe built formulations in which the optical brighteners of the invention can be employed. These compositions provide pH's in the range of 8.5-11.5. The invention is not limited by these examples, however, which are merely illustrative.

EXAMPLE X

	Percent
Sodium soaps of 80:80 coconut:tallow fatty acids	35
Sodium silicate	60
Tetrasodium pyrophosphate	10
Sodium chloride	40
Disodium 4,4'-(2-benzisothiazolonyl-S-dioxide)-2,2'-stilbenedisulfonate	5
Moisture	0.05
	Balance

The composition launders well and exhibits good brightening properties on cotton fabrics.

EXAMPLE XI

A granular built synthetic detergent composition having the following formulation can be prepared with the brightening agents of this invention incorporated therein. The composition, in addition to performing well in its

cleaning capacity, imparts effective fluorescence to fabrics cleaned in the solution.

	Percent
Sodium linear dodecyl benzene sulfonate	17.5
Sodium tripolyphosphate	50
Sodium sulfate	14
Sodium carboxymethylcellulose	0.5
Sodium silicate	7
Disodium 4,4'-(o-disulfophenylimidinyl)-2,2'-stilbenedisulfonate	0.10
Moisture	Balance

EXAMPLE XII

The following granular composition containing an effective chlorine bleaching agent performs very well in cleaning, whitening and brightening:

	Percent
Sodium tallow alkyl sulfate	7
Sodium linear dodecylbenzenesulfonate	7
Sodium tripolyphosphate	50
Sodium carbonate	10
Sodium sulfate	10
Potassium dichlorocyanurate	15
4,4'-(2-benzisothiazolyl-S-dioxide) - 2,2' - stilbene-sulfonate	0.05
Moisture	Balance

EXAMPLE XIII

A built liquid laundering composition which brightens as it cleans and which is suitable for laundering household fabrics can have the following composition:

	Percent
Sodium-3-dodecylaminopropionate	6
Sodium linear dodecylbenzenesulfonate	6
Potassium pyrophosphate	20
Potassium toluene sulfonate	8
Sodium silicate	3.8
Carboxymethyl hydroxyethyl cellulose	0.3
4-(2-benzisothiazolyl-S-dioxide) - 4' - (1 - phthalimidinyl)-2,2'-stilbenedisulfonate	0.05
Water	Balance

This detergent composition is effective in laundering and brightening resin-treated cotton "wash and wear" fabrics.

EXAMPLE XIV

A household laundering composition has the following ingredients:

	Percent
Sodium salt of SO ₃ -sulfonate tetradecene	10
Dimethyl coconut alkyl ammonium acetate	10
Trisodium ethane-hydroxy triphosphonate	60
Sodium carbonate	10
4,4'-(2-benzisothiazolyl-S-dioxide) - 2,2' - stilbene-disulfonamide	0.10
Moisture	Balance

This composition brightens as it cleans and can be usefully employed in laundering nylon fabrics.

EXAMPLE XV

An effective granular detergent composition has the following formulation:

	Percent
Sodium linear dodecylbenzenesulfonate	7.5
Sodium tallow alkyl sulfate	2
Hydrogenated marine oil fatty acid suds depressant	2.2
Sodium tripolyphosphate	40
Trisodium nitrilotriacetate	20
Sodium silicate (ratio SiO ₂ :Na ₂ O of 2:1)	10
Sodium sulfate	13
4-(2-benzisothiazolyl - S - dioxide)-4'-2,2'-stilbenedisulfonamide	0.5
Water	Balance

25
EXAMPLE XVI

Another effective granular detergent has the following composition:

	Percent
Sodium linear dodecylbenzenesulfonate	10
Condensation product of 1 mole of nonyl phenol with 12 moles of ethylene oxide	5
Sodium tripolyphosphate	10
Trisodium ethane-1-hydroxy-1,1-diphosphonate	30
Trisodium nitrilotriacetate	10
Sodium silicate (ratio of $\text{SiO}_2:\text{Na}_2\text{O}$ of 2:1)	6
Trisodium phosphate	10
Sodium carboxymethyl cellulose	0.5
Sodium 4-(2-benzisothiazolonyl - S - dioxide)-2-stilbenesulfonate	0.1
3-phenyl-7-(o-disulphenylimidinyl)coumarin	0.2
Moisture	Balance

EXAMPLE XVII

A laundering-brightening composition, especially effective on cotton fabrics at cool water temperatures, has the following composition:

	Percent
Sodium tallow alkyl sulfate	5
3-(N,N-dimethyl-N-dodecylammonio) - 2 - hydroxypropane-1-sulfonate	12
Sodium salt of SO_3 -sulfonate α tridecene	5
Sodium tripolyphosphate	30
Trisodium nitrilotriacetate	20
Sodium silicate ($\text{SiO}_2:\text{Na}_2\text{O} = 1.6:1$)	10
Sodium sulfate	10
Sodium carboxymethyl hydroxyethyl cellulose	0.3
3 - phenyl-7-(2-benzisothiazolonyl-S-dioxide)coumarin	0.1
3-phenyl-7-(2-benzisothiazolyl - S - dioxide)-coumarin	0.1
Moisture	Balance

The aqueous and granular bleach composition of this invention are exemplified by the following examples which are formulations in which the optical brighteners of the invention can be employed. The invention is not, however, limited by these examples which are merely illustrative.

EXAMPLE XVIII

An excellent aqueous bleach composition which improves the whitening of bleached textiles has the following composition:

	Percent
Sodium hypochlorite	5.2
Disodium 4-(2-benzisothiazolonyl - S - dioxide) - 4' - phthalimidinyl-2,2'-stilbenedisulfonate	0.2
Water	Balance

EXAMPLE XIX

An aqueous bleach having advantageous bleaching and whitening has the composition:

	Percent
Sodium hypochlorite	5.2
Disodium 4-(2-benzisothiazolyl-S-dioxide) - 4' - (2-phthalimidinyl)-2,2'-stilbenedisulfonate	0.05
Water	Balance

26
EXAMPLE XX

The following granular bleach composition which dissolves readily in a household automatic washing machine has the following composition:

	Percent
Potassium dichlorocyanurate	65
Sodium linear dodecylbenzenesulfonate	6
Potassium pyrophosphate	25
Disodium 4-(1-isindolinyl) - 4' - (2-benzisothiazolonyl-S-dioxide)-2,2'-stilbenedisulfonate	3
Moisture	0.3
Sodium sulfate	Balance

Similar results are obtained when sodium dichlorocyanurate is employed in place of potassium dichlorocyanurate in that a bleaching and brightening composition is obtained.

The foregoing description of the invention has been presented describing certain operable and preferred embodiments. It is not intended that the invention should be limited since variations and modifications thereof will be obvious to those skilled in the art, all of which are within the spirit and scope of this invention.

What is claimed is:

25 1. A compound of the formula

wherein each a is an integer of from 1 to 4; each A is selected from hydrogen; alkyl of 1 to 10 carbon atoms; halogen; alkoxy of from 1 to 10 carbon atoms; aryl of from 6 to 12 carbon atoms; alkylsulfonyl of from 1 to 10 carbon atoms; alkoxyalkyl of from 2 to 10 carbon atoms; polyethoxy of the formula $\text{H}(\text{CH}_2\text{CH}_2\text{O})_n$ — where n is an integer from 1 to 10; haloalkyl of from 1 to 10 carbon atoms; alkanoyl of from 2 to 10 carbon atoms; cyano; polyhydroxyalkyl of from 1 to 10 carbon atoms; 45 X is selected from

and each p is 1 or 2.

2. A compound according to Claim 1 which is 3-phenyl-7-(o-disulphenylimidinyl) coumarin.
